Primary Examiner — Robert M Spear*Assistant Examiner* — Kendra L Hamilton**CLAIM**

An ornamental design for a steering wheel cover with keyboard grip, as shown and described.

DESCRIPTION

FIG. 1 is a perspective front view of a steering wheel cover with keyboard grip, showing my new design;
 FIG. 2 is a front view thereof, illustrated on an unclaimed steering wheel;
 FIG. 3 is a back view thereof;
 FIG. 4 is a left side view thereof;
 FIG. 5 is a right side view thereof;
 FIG. 6 is a top view thereof; and,
 FIG. 7 is a bottom view thereof.

The broken lines shown represent unclaimed subject matter and form no part of the claimed design.
